UNITED STATES PATENT OFFICE.

FRANCIS M. CROSSETT, OF VERONA, NEW YORK, ASSIGNOR OF ONE-HALF TO BARBARA CATHARINE CROSSETT, OF VERONA, NEW YORK.

NON-REFILLABLE BOTTLE.

1,087,729.

Specification of Letters Patent. Patented Feb. 17, 1914.

Application filed June 10, 1913. Serial No. 772,818.

To all whom it may concern:

Be it known that I, FRANCIS M. CROSSETT, a citizen of the United States, residing at Verona, in the county of Oneida and State of New York, have invented new and useful Improvements in Non-Refillable Bottles, of which the following is a specification.

The invention relates to bottles, and more particularly to bottles of the non-refillable type, and has for an object to provide a bottle that cannot be conveniently refilled after the original contents have once been withdrawn therefrom.

The invention embodies, among other features, the provision of a bottle body including a neck in which is movably arranged a valve normally closing a passage from the bottle body to the neck, with a baffle member carried within the neck to prevent the insertion of instruments or wires therein in an endeavor to secure the valve in a position to permit of refilling the bottle with a spurious fluid, the said baffle member further constituting a means for limiting the movement of the valve in the neck of the bottle body.

In the further disclosure of the invention reference is to be had to the accompanying drawings, constituting a part of this specification, in which similar characters of reference denote corresponding parts in all the views, and in which:

Figure 1 is a fragmentary vertical sectional view of my device, showing the valve in closed position; Fig. 2 is a sectional view showing the valve in open position, the baffle member being shown in side elevation; Fig. 3 is a vertical transverse sectional view taken through the baffle member.

Referring more particularly to the views, I provide a bottle body 10 including a neck 11, with a seat 12 formed within the neck 11 at its juncture with the bottle body 10, thus providing a passage 13 from the bottle body to the neck. The passage 13 is normally closed by a valve 14 consisting of a semi-circular head 15 and a tapered shank 16, the said head 15 being adapted to normally repose on the seat 12 to close the passage 13, with the shank 16 depending within the passage. A continuous groove 17 is formed on the inner surface of the neck 11 of the bottle body 10 and is adapted to receive therein the projecting ends of a substantially U-shaped spring 18, the said spring constituting a securing member for

a baffle member 19 arranged within the neck of the bottle body. The baffle member is of a substantially tubular construction, with the top thereof closed and provided with a series of spiral grooves 20 in the side. The lower end of the baffle member is open in order that the spring 18 can be arranged therein so that its ends will project through a plurality of slots 21 formed in the baffle member, and the lower end of the baffle member is then preferably closed by a suitable plug 22. A plurality of side openings 23 are formed in the baffle member 19 above and below the spring 18, and when the plug 22 has been arranged on the baffle member to close the lower end thereof and the said baffle member arranged within the neck of the bottle body, it will be apparent that upon tilting the bottle body the contents of the bottle body, passing therefrom into the neck, will have to pass into the lower side opening 23 and thence through the tubular portion of the baffle member and outwardly through the upper side opening 23, while at the same time a quantity of the fluid can also trickle through the spiral grooves 20 formed in the face of the baffle member.

It will be readily apparent that in the use of the device described the bottle body is first filled with the desired fluid, after which the valve 14 is permitted to drop into the neck and gravitate into position on the seat 12 to close the passage 13, with the shank 16 depending within the passage. The baffle member 19 is now inserted in the neck of the bottle body and when the ends of the spring align with the groove 17 it will be apparent that the said ends will spring into the groove and lock the baffle member within the neck, the said baffle member being now in position so that when the bottle body is tilted and the valve 14 gravitates into open position to uncover the passage 13 the head 15 of the valve will engage the plug 22 so that the baffle member will limit the movement of the valve with respect to its seat and the passage which it normally closes.

It should be noted that the shank 16 is made sufficiently long so that when the valve is in extreme open position, with the head 15 abutting against the under side of the plug 22, the lower end of the shank will still engage the restricted portion of the neck which forms the valve seat 12 so that

the valve cannot be improperly displaced or become lodged in inoperative position in the neck due to the tilting of the bottle body.

5 Having thus described my invention, I claim:

In a non-refillable bottle, the combination with a bottle body including a neck provided with a passage to the bottle body, of
10 a valve seat in the neck, a valve normally reposing on the seat and extending into the passage to close the same, a hollow baffle member open at its lower end within the neck and having a plurality of openings
15 communicating with a chamber in the neck,

a U-shaped spring arranged within the baffle member and having its ends projecting through apertures in the wall of the baffle member and into a groove formed in the neck, for locking the baffle member within 20 the neck, and a plug closing the lower end of the baffle member and engaging the spring for holding the same in rigid position within the baffle member.

In testimony whereof I affix my signature 25 in presence of two witnesses.

FRANCIS M. CROSSETT.
